UNITED STATES PATENT OFFICE.

BENJAMIN FRANKLIN MORTON, OF HOBOKEN, PENNSYLVANIA.

1,295,564

GLASS-ANNEALING FURNACE.

1,295,564

Specification of Letters Patent. Patented Feb. 25, 1919.

Application filed September 13, 1918. Serial No. 253,948.

To all whom it may concern:

Be it known that I, BENJAMIN FRANKLIN MORTON, a citizen of the United States, residing at Hoboken, Allegheny county, Pennsylvania, have invented a new and useful Improvement in Glass-Annealing Furnaces, of which the following is a full, clear, and exact description, reference being had to the accompanying drawings, forming part 10 of this specification, in which—

Figure 1 is a longitudinal section through one form of my improved furnace.

Fig. 2 is a sectional view on the line II—II of Fig. 1.

Fig. 3 is a similar view on the line III—III of Fig. 1.

Fig. 4 is an irregular sectional view on the line IV—IV of Fig. 1, and

Fig. 5 is a perspective view of a portion 20 of one of the compound muffle roof arches.

This invention relates to an improvement in annealing furnaces, and more particularly to furnaces of the muffle type for annealing glassware.

The object of my invention is to provide 25 a furnace of this character in which glassware is annealed in a muffle within the combustion chamber out of contact with the gases used for heating the furnace, and is 30 designed to provide a cheap and efficient structure of this character, in which the muffle is so constructed that there will be no leakage of gases from the combustion chamber into the muffle; and in which the muffle 35 is supported by two sets of arches within the combustion chamber. Another object of my invention is to provide metallic supports for the roof of the muffle as well as the roof of the combustion chamber, which 40 may be used in cases of very large structures.

The precise nature of my invention will be best understood by reference to the accompanying drawings, which will now be 45 described, it being premised, however, that various changes may be made in the details of construction and general arrangement of the parts, without departing from the spirit and scope of my invention as defined in the 50 appended claims.

In the drawings, the reference character 2 designates the side walls of the furnace and 3 the usual buckstays on each side thereof for retaining the side walls in position. 4, 55 4 are air ducts on each side of the structure, in the bottom thereof, which are provided

with air inlets 5, and 6 is a gas duct between the air ducts 4, which is separated therefrom by means of the longitudinal walls 7. The front end of the gas duct is in communication with a gas flue 8 by means of a port 9, which is controlled by a valve 10. The tops of the air ducts 4 and the gas duct 6 are formed of tiles 11, which are supported on portions of the side walls 2 and the longitudinal walls 7, and which tiles also form the bottom of the combustion chamber 12. 60 13 are openings in the tiles 11 through which the air flows into the combustion chamber 12, and 14 are similar openings through the tiles for admitting the gas from the gas duct 6 into the combustion chamber. In the drawings I have shown the gas and air ducts on one side in staggered relation to the gas and air ducts on the other sides of the furnace, but it will readily be understood that these may be placed in any desired manner, in accordance with the requirements of the 65 furnace.

Supported on the lower portion of the 80 wall 2 and within the combustion chamber on each side thereof, are a plurality of vertical piers 15, which form abutments for arches 16. These arches 16 form the support for the bottom 17 of a muffle 18, while the bottom 17 of the muffle and the arches 16 form the top of the main combustion 85 chamber 12. Supported on the bottom tile 17 and the arches 16 are the side walls 19 of the muffle, and 20 is the roof of the furnace or combustion chamber.

The roof of the muffle is formed of a plurality of T-shaped tiles 21, which in turn support tiles 22. The tiles 21 and 22 form the roof of the muffle 18. 22 are T-shaped tiles, the flanges of which straddle the legs of the T-shaped tiles 21, and together form composite arches for supporting the roof of the muffle. The end tiles of each of these arches rest against the upper 100 ends of the piers 15 which form abutments for the arches. By supporting the tiles 22 between the arch forming tiles 21 and 23, gas tight joints are formed between the roof of the muffle and the combustion chamber.

24 are longitudinal walls supported on the roof 20 of the furnace, and formed between these walls is a flue 25, the end walls thereof being supported on the end walls 26 of the furnace. Communicating with this flue 26 is an offtake flue 27. The opening

thereto may be regulated by means of a damper 28. The combustion chamber at the side of the muffle and the top thereof is divided into a plurality of secondary combustion chambers 29, each of which is in communication with the main combustion chamber by means of ports 30 and 31 at the lower end thereof, while the central upper portion of each of these secondary chambers is in communication with the flue 26 by means of a port 32.

These ports 32 may be entirely or partially closed by means of movable tiles or dampers 32^a which extend through one of the walls 24, so that the temperature in the different portions of the muffle may be readily regulated.

In the drawings I have shown the portions of the buck-stays 3 connected to each other by means of cross members 33 which are connected thereto by means of angle irons 34 and which cross members also form supports for the offtake flue 27. These members 33 also form supports for longitudinal channel members 35, to which are connected the ends of rods 36. These rods 36 extend downwardly through the roof 20 and the tiles 21 and 23 of the arches, and have heads 37 on the lower end thereof for forming auxiliary supports for the arches. These auxiliary supports may be used in cases where large furnaces are constructed, but in small furnaces, it is not necessary to provide auxiliary supports for supporting the arches.

In the drawings the walls 2 have been extended upwardly above the roof 20 to form auxiliary supports for the cross members 33, but if desired these extensions of the walls may be omitted.

It will also be understood that the buck-stays may be connected to each other in the usual manner instead of by means of the members 33 which form supports for the longitudinal members 35.

I have shown, in the drawings, a plurality of longitudinally extending tiles 38 along the joints between the bottom tiles 17 of the muffle. These tiles may be used for supporting the usual runway for the pans in which the articles to be annealed are placed, and also form seals for the joints between the tiles 17 as well as flues under the pans for permitting a free circulation.

The front end of the muffle is provided with an inlet opening 39 through which the articles to be annealed are passed, while the rear end of the muffle is in communication with the usual cooling extension 40 of a glass annealing leir.

The advantages of my invention result from the provision of a glass annealing furnace having a muffle within the combustion chamber, which is supported between the arches in the bottom of the combustion

chamber and arches in the top of the combustion chamber. Another advantage of my invention results from the provision of a compound arch for supporting the roof of the muffle, together with means for interlocking the roof tiles for the muffle between said arches. Furthermore, from the provision of means for forming gas tight joints between the muffle and the combustion chamber, together with means for preheating the air and gas by the heat from the bottom of the combustion chamber before admitting the air and gas to the combustion chamber.

I claim:

1. A glass annealing furnace having a combustion chamber, a plurality of upper arches therein, a plurality of lower arches therein, and a muffle supported on said arches, substantially as described.

2. A glass annealing furnace having a combustion chamber, a plurality of upper arches therein, a plurality of lower arches therein, a muffle bottom and side walls supported on the lower arches, a roof for the muffle supported on the upper arches, and a roof for the combustion chamber above the upper arches, substantially as described.

3. A glass annealing furnace having a combustion chamber, a plurality of upper arches therein, a plurality of lower arches therein, a muffle bottom and side walls supported on the lower arches, a roof for the muffle supported on the upper arches, a roof for the combustion chamber above the upper arches, and supporting rods for some of the upper arches, substantially as described.

4. A glass annealing furnace having a combustion chamber, a plurality of arches therein, a muffle supported on said arches, upwardly extending piers therein, a plurality of arches supported on said piers, and a roof for the muffle supported on the last mentioned arches, substantially as described.

5. A glass annealing furnace having a combustion chamber, a plurality of arches in the lower portion of the combustion chamber, upwardly extending piers on each side of the combustion chamber, arches on said piers, a muffle within the combustion chamber between the piers and the arches, substantially as described.

6. A glass annealing furnace having a combustion chamber, a muffle within said combustion chamber, a plurality of arches in the lower portion of the combustion chamber for supporting the bottom and side walls of the muffle, a plurality of compound arches in the top of the combustion chamber, a roof for the combustion chamber above said arches, and a plurality of tiles forming the roof of the muffle supported between the members of the compound arches, substantially as described.

7. A glass annealing furnace having a

main combustion chamber, a plurality of arches in the combustion chamber, a muffle supported by said arches, there being a plurality of auxiliary combustion chambers 5 along the side walls and the top of the muffle, communicating with the main combustion chamber, arches for supporting the roof of the muffle, a flue in communication with all of said secondary combustion chambers, 10 and an offtake flue in communication with the last mentioned flue, substantially as described.

8. A glass annealing furnace having a combustion chamber, gas and air flues below 15 said combustion chamber, means for admitting gas to the gas flue, means for admitting air to the air flues, ports leading from the

gas and air flues to the combustion chamber, a plurality of arches in the lower portion of the combustion chamber, a plurality of piers 20 on each side of the combustion chamber, said piers being approximately in vertical alignment with the arches, a second set of arches supported on said piers, a roof above said arches, a longitudinal flue above the roof 25 communicating with the combustion chambers between the second set of arches, an offtake flue in connection with the last mentioned flue, and a muffle in the combustion chamber supported between the arches and 30 the piers, substantially as described.

In testimony whereof, I have hereunto set my hand.

BENJAMIN FRANKLIN MORTON.
